UNITED STATES PATENT OFFICE.

CHARLES F. KRAMER, OF MONDOVI, ASSIGNOR OF TWO-THIRDS TO JOHN HIGGINS, OF EAU CLAIRE, WISCONSIN.

CONVERTIBLE CHAIR.

SPECIFICATION forming part of Letters Patent No. 447,482, dated March 3, 1891.

Application filed July 15, 1889. Serial No. 317,636. (No model.)

To all whom it may concern:

Be it known that I, CHARLES F. KRAMER, of Mondovi, Wisconsin, a citizen of the United States, have invented a new and useful Convertible Chair, of which the following is a full description.

This invention relates to furniture, and more especially to that class thereof known as convertible chairs; and the object of the same is to provide a single chair whose seat is made up of a number of stools, the latter being removable from the chair and the back of the chair being capable of turning down to form a table-top, all as hereinafter more fully described, and as illustrated in the accompanying drawings, in which—

Figure 1 is a side elevation of my convertible chair complete. Fig. 2 is a section of the same, showing one of the stools in position and another as being withdrawn. Fig. 3 is a similar section through the chair-frame, but showing the back turned down, whereby it is converted into a table; and Figs. 4 and 5 are respectively a side and rear elevation of one of the stools.

Referring to the said drawings, the letter F designates the frame-work of the chair, which is mounted upon casters C, that roll upon the floor, and the arms A of which are upholstered, as shown at U. B is the back of the chair, which is upholstered at U on its front face, and to each side of this back is connected a long slotted arm O, whose slot engages a pin P on the inner side of each arm. By this construction the back B can be used as such, as shown in Fig. 2, or can be turned upon the pins to form a table-top, as shown in Fig. 3.

The side bars f, which connect the four legs L of this frame, are of ordinary construction, and are rigidly secured at their ends to the legs; but the front and rear bars R are carried by brackets K, whose inner ends are connected by pivots p to the side bars f. By this construction when the front and rear bars are down, as shown in Fig. 3, a rectangular space is formed within the body of the chair, the latter then having no seat, and when one or both of the swinging bars R are turned up, as shown in Fig. 2, a stool S may be passed into the frame-work F, as will be understood.

Each stool comprises a suitable standard S', with a seat E, which may be mounted upon the standard through a screw U', as shown, although this is not absolutely necessary. 55 The back D of the stool is connected by pins or pivots b to its seat in such a manner that it may be turned down in rear of the same, as shown in Fig. 2. A brace J is pivoted at M to a cross-bar of the back and has a pin m in the inner side of its free end. To the rear of the seat is secured a plate N, having an L-shaped slot or opening n therein, as shown. When the back D is raised, the brace J is swung to the position shown in dotted lines 65 in Fig. 5, its pin m inserted in the recess n, and the brace returned to a vertical position. The back D is thus braced in a manner which will be readily understood.

In operation the chair, as shown in Fig. 1, 70 comprises the back, arms, and legs of the frame-work F; but its seat is composed of the seats E of four stools S, which stand within its frame-work and are retained there by the side pieces f and the front and rear pieces R. 75 When it is desired to use this chair as a table, said front and rear pieces are turned up, the four stools drawn out, their backs turned up and braced, and the back B of the chair turned down to a horizontal position, as shown 80 in Fig. 3. The stools may then be used for persons sitting around the table. In order that the entire chair may be moved over the floor, I prefer to provide the stools also with casters, although these have not been shown. 85

Having described my invention, what I claim is—

1. The herein-described convertible chair, the same comprising back, arms, a frame-work having one swinging side and legs at 90 the four corners of said frame-work, and a number of stools removably inserted within said frame-work and of a size to be withdrawn from the swinging side thereof, their seats forming the seat of the chair, substantially 95 as set forth.

2. In a convertible chair, the combination, with the frame-work F, having the stationary side pieces f, the front and rear pieces R, and the brackets K, connected to said front and 100 rear pieces and mounted on pivots p in the side pieces, of the stools S, of a size to pass

into the frame-work when the front and rear pieces are thrown back, the seats E of said stools forming the seat of the chair, substantially as set forth.

5. In a convertible chair, the combination, with the frame-work F, mounted upon legs L, and the removable pieces R, supported by brackets K, pivotally connected to said frame-work, of the stools S, whose seats form the seat for the chair, each stool having an independent standard of its own, and the back D, adapted to be lowered when the stools are assembled within the frame-work, substantially as set forth.

15 4. The stool S, comprising a seat E, supported on a standard, a back D, pivoted to said seat, a brace J, pivoted at M to a cross-bar of the back and having a pin m in its lower end, and a plate N, secured to the rear edge of the seat and having an L-shaped recess n, adapted to be engaged by said pin, the

whole operating substantially as hereinbefore set forth.

5. The herein-described convertible chair, the same comprising back, arms, a frame-work having one swinging side and legs at the four corners of said frame-work, and a number of stools removably inserted within said frame-work side by side and of a size to be withdrawn from the swinging side thereof, 25 their seats forming the seat of the chair, and each stool being supported upon its own legs independent of the legs of the frame-work, and having hinged backs D, swinging backward so as to depend below the seat and leave 30 the latter unobstructed when the stools are assembled within the frame-work, substantially as set forth.

CHAS. F. KRAMER.
